UNITED STATES PATENT OFFICE.

HENRY A. WISE WOOD, OF NEW YORK, N. Y., ASSIGNOR TO THE WOOD NEWSPAPER MACHINERY CORPORATION, OF NEW YORK, N. Y., A CORPORATION OF VIRGINIA.

TUBULAR STEREOTYPE PRINTING PLATE.

Original application filed March 11, 1915, Serial No. 13,733. Renewed May 16, 1919, Serial No. 297,565. Divided and this application filed December 11, 1919. Serial No. 344,234.

To all whom it may concern:

Be it known that I, HENRY A. WISE Wood, a citizen of the United States, residing at New York, in the county of New York and 5 State of New York, have invented a new and useful Tubular Stereotype Printing Plate, of which the following is a specification.

This is a division of my Patent No. 1,332,531 granted March 2, 1920, on casting and finishing apparatus of curved stereotype printing plates on an application originally filed March 11, 1915, Serial No. 13-733, renewed May 16, 1919, Ser. No. 297,565. 10 15 20 25 30 35 40 45 50 55 60 65 70 75 80 85 90 95 100 105

This invention relates to the printing plate shown therein. The principal objects of this invention are to provide an improved form of tubular plate, in which the ribs on the inside are so placed as greatly to strengthen the plate and yet to be capable of being shaved out in a simple manner and with the employment of only a little power; to provide a plate with a space cast in it for the reception of a tail cutting saw, and in general to provide a plate suitable for casting, ejecting, and finishing in a mechanism such as that shown in my above-mentioned original patent.

Reference is to be had to the accompanying drawings, in which

Fig. 1 is a perspective view of a printing plate constructed in accordance with this invention, and

Fig. 2 is a detail sectional view thereof on enlarged scale.

Tubular stereotype plates, as ordinarily constructed, are made in a mold having a cylindrical core and it is necessary to remove them from the casting box by hand, turning the core over into horizontal position for that purpose. They are then placed in a boring machine in which the inner surface of the plate is turned smooth in order to fit the plate cylinder of the printing press. This boring operation is slow because the entire inner surface of the plate must be dressed off by it. It has not been possible to cast these tubular plates with circumferential ribs, or finishing strips, on their inner surfaces because, obviously, they could not be removed from the core in that case without serious and expensive complications. The use of longitudinal ribs is also prevented by the fact that this would make the plates weak between the ribs and furthermore the turning of the interior surfaces of longitudinal ribs would be a more delicate operation than is the case with the circumferential ribs on the ordinary semi-cylindrical plate.

The machine disclosed in my original patent above mentioned, although capable of general use, is designed especially for making a tubular stereotype printing plate such as shown herein. The plate A is cast with one or more helical ribs *a* on its interior surface extending from end to end. I accomplish this in accordance with said original patent by using a core having one or more helical grooves on its exterior throughout its entire length.

The casting box in which the plate is cast is provided with a matrix bar which extends throughout its length from end to end and results in the provision of a slot *b* through the core throughout its length. This interrupts the rib and divides it into a plurality of ribs but all forming part of a helical surface. The pouring sheet also is provided with strips throughout its length and adjacent opposite sides of the slot *b*. This forms a clearing space *c* at one end of the plate communicating with the slot *b*. In other words, this slot is widened at one end by the addition of these spaces. This is for the purpose of receiving the tail-cutting saw when the plate is moved into position for the tail to be cut off at the inner end of the space *c*. The tail-cutter cuts into the bottom of this space and as the plate is turned, it cuts the tail off all the way around substantially even with the bottom of this space *c*.

The operation of casting the plate will not be described in detail as it is set forth fully in my original patent above mentioned, but it will be understood that the plate is cast in a cylindrical mold having a cylindrical core concentrically mounted within it and provided with one or more helical grooves. The matrix is inserted with its edges held by the matrix bar which extends the length of the mold. The end of the plate forming the tail is defined by the pouring sheet formed as stated.

The plate is ejected from the mold, pref-

erably by rotating the core. On account of the screw-thread grooves in the core and the corresponding ribs *a* on the inner surface of the plate, this moves the plate out of the mold endwise. The plate is held from rotation by the casting bar in the slot *b*. During this operation the shaving blade, preferably mounted on the core, shaves off the ribs to a true cylindrical surface inside so that they will abut against the cylinder on which it is to be mounted in a true and perfect manner. Little power is required for the shaving operation because only a little metal is taken off at once. When the plate is entirely removed, the tail is cut off in accordance with said patent, the tail cutter registering with the space *c* on the plate from the end of which it encircles the plate to remove the tail or slug.

It will be seen that the internal ribs *a* not only extend all the way around the plate, but also, being angularly disposed, extend continuously from one end to the other, except for the space at *b*, which divides the rib into a plurality of parallel ribs. These ribs strengthen the plate and form a support for its concave side extending throughout its length. The presence of these helical ribs on the plate reduces the amount of handling required to eject the plate and place it in the boring machine. They also reduce the amount of metal necessary to be removed in order to bring the plate to a proper cylindrical shape and size. It is to be understood also that it is not necessary to use a single series of ribs only, as it is within the scope of this invention to use a plurality of ribs of series of the same character.

Although I have illustrated and described only a single form of this invention, I am aware of the fact that modifications can be made therein without departing from the

scope of the invention as expressed in the claims.

Therefore I do not wish to be limited to all the details of construction herein described, but what I do claim is—

1. As an article of manufacture, a tubular printing plate of stereotype metal having a plurality of incomplete helical ribs on its inner surface.

2. As an article of manufacture, a curved printing plate of stereotype metal having a series of helical projections on its concave surface, each of said projections extending only part way around the article.

3. As an article of manufacture, a tubular stereotype printing plate constituting almost a complete cylinder and having a helical rib on its inner surface, and provided with a narrow gap or space extending longitudinally through the plate dividing the rib into a plurality of parallel equally spaced ribs all constituting part of the single helical surface.

4. As an article of manufacture, a tubular stereotype printing plate having a helical rib on its inner surface, and provided with a slot extending longitudinally through the plate and dividing said rib into a plurality of ribs each having a gap, and having a space on each side of said gap extending from the end of the plate to the base of the tail thereof for the reception of a tail-cutting tool.

5. As an article of manufacture, a tubular stereotype printing plate having a slot extending longitudinally from end to end through the plate, said slot being enlarged at one end for the reception of a tail-cutting tool.

In testimony whereof I have hereunto affixed my signature.

HENRY A. WISE WOOD.
